UNITED STATES PATENT OFFICE.

ALEXANDER LILJA, OF NOTI, OREGON.

WHISTLE-CONTROLLING ATTACHMENT.

Application filed July 9, 1923. Serial No. 650,284.

To all whom it may concern:

Be it known that I, ALEXANDER LILJA, a citizen of the United States, residing at Noti, in the county of Lane and State of Oregon, have invented certain new and useful Improvements in Whistle-Controlling Attachments, of which the following is a specification.

This invention relates to whistle controlling devices for use, more especially, with log-hauling or donkey engines.

In logging operations the usual practice is to have the whistle-valve operating arm connected to a pull line or wire extending into the woods to enable an operator there sounding the whistle for signalling the engineer to start or stop the winding drum of the log-hauling cable.

Whistle operating devices of this character are frequently broken or disarranged by trees, branches, etc., falling on the controlling line which results in accidents, injury to the equipment and other troubles.

With these and other conditions in view my invention has for its object to provide devices interposed between the pull wire and the whistle and through the medium of which the whistle is actuated and the whistle and its connections with the engine are safeguarded from injury.

A further object is to provide means whereby quick and sharp pulls may be imparted to the valve arm instead of the slower applications effected by other appliances.

Still other objects and advantages of the invention will appear in the following specification.

The invention consists in the novel construction, adaptation and combination of parts hereinafter described and claimed.

In the accompanying drawing,—

Figure 1 is an elevational view of a portion of the boiler of a donkey engine, the engine whistle and whistle controlling devices embodying my invention. Fig. 2 is a side elevation of the whistle controlling devices to a larger scale than in Fig. 1.

In said drawing, the reference numeral 5 designates a donkey engine boiler, and 6 is a whistle operatively connected thereto. 7 designates the whistle valve which is normally held in its closed position by means of a spring (not shown) and is moved into its open position by means of an arm 8 secured to the stem of the valve to render the whistle operative.

According to the present invention instead of connecting the operating line 9 directly to the valve arm 8, as heretofore, I connect said line 9 to an end of a drag bar 60 11. This drag-bar is mounted for longitudinal reciprocating movements in guide elements 12 and 13 of a frame 14 which is secured as by means of bolts 14¹ to a rigid support such as the roof 15 of the house 65 provided for the associated engine.

At the opposite end from its connection with the operating line 9, said bar is connected by a pivot pin 16 with a lever 17 which is pivotally connected by a fulcrum 79 pin 18 to a lug element 19 of the frame 14.

The lever 17 is connected, as shown, by a wire 20, or other suitable flexible connection with the valve-stem arm 8.

21 represents a spring provided on the 73 drag bar 11 between the frame guide 12 and a set collar 22 which is provided on said bar, said collar being engageable against the frame guide 13 which acts as a stop whereby the spring 21 serves to yieldingly hold the 69 lever 17 in its normal full line position corresponding to the closed position of the whistle valve. The dotted line position 17¹ of said lever represents the same in its retracted position which corresponds with the 55 position of the valve to sound the whistle.

The throw or movement of the lever 17 is regulated by an adjusting stop screw 23 provided in a threaded hole in the guide 13 acting in cooperation of the set collar 22 93 with respect to the guide 13.

In operation, a pull applied to the line 9 in the direction of arrows in the respective views acts through the medium of the drag-bar 11 and lever 17 to draw the latter from 95 its full line position to that in which it is indicated by dotted lines 17¹ to effect the blowing of the whistle.

In such operation the spring 21 is contracted and upon the operator releasing the 100 pull line, said spring acts to return the drag-bar into the position in which it is illustrated together with the lever 17 into its full line position. The set collar 22 is located to limit the swing of the lever 17 in 105 one direction and the stop screw 23 serves to limit the swing of the lever in the opposite direction.

By means of such devices the whistle and its valve are safeguarded from injury by any 110 violent pull imparted to the pull line 9. The spring 21 serves to relieve the whistle

mechanism from stresses due to the weight of the pull line and ensures a rapid closing of the whistle valve to produce a sharp blast.

The frame 14 is advantageously provided 5 with an apertured post element 24 which serves as a guide or "fair leader" for the pull-line 9 with respect to the drag-bar 11.

The preferred construction of the invention 10 and the operation thereof will, it is thought, be understood from the foregoing description.

I do not limit myself to the specific construction shown as changes may be made within the scope of the following claims.

15 What I claim, is,—

1. A whistle control attachment embodying 20 a whistle valve actuating lever, a guide element, means receivable in the guide element and connected with the actuating lever for moving the same, a combination adjusting and stop member carried by the guide element and adapted to intercept the lever at a predetermined point in its path of travel, and a combination adjusting and stop 25 member carried by the means for moving the lever for regulating the movement of said means, said adjusting and stop members being disposed for independent and relatively parallel movement along a line defined by the longitudinal axis of the lever moving means.

2. A whistle control attachment embodying 30 a whistle valve actuating lever, a guide element, a drag bar receivable in the guide element and connected with the actuating lever for moving the same, a combination adjusting and stop screw carried by the

guide element and adapted to intercept the lever at a predetermined point in one of the sectors of its path of travel, and a combination adjusting and stop collar carried by the drag bar and adapted to abut against the guide member to limit the movement of the lever at a predetermined point in another sector of its path of travel, said adjusting 40 screw and stop collar being disposed for independent and relatively parallel movement along a line defined by the longitudinal axis of the drag bar.

3. A whistle control attachment embodying 45 a whistle valve actuating lever, an elongated support for the lever, a plurality of aligned, spaced guide elements formed on the support, a drag bar receivable in certain of said guide elements and connected 50 with the actuating lever for reciprocation parallel with the longitudinal axis of the support and tangentially to the arc of rotation of the lever, a combination adjusting and stop member carried by one of the guide elements and adapted to intercept the lever at a predetermined point in its path of travel, and a combination adjusting and stop member carried by the drag bar, said 55 adjusting and stop members being disposed for independent and relatively parallel movement along a line defined by the longitudinal axis of the drag bar.

Signed at Noti, Oregon, this 25 day of June, 1923.

ALEXANDER LILJA.
